UNITED STATES PATENT OFFICE.

GEORGE WRIGHT, OF EAST ORANGE, NEW JERSEY.

DOCK-PIER CONSTRUCTION.

Application filed November 20, 1919. Serial No. 339,276.

To all whom it may concern:

Be it known that I, GEORGE WRIGHT, a citizen of the United States, and a resident of East Orange, in the county of Essex and

State of New Jersey, have invented certain new and useful Improvements in Dock-Pier Constructions, of which the following is a full, clear, and exact description.

Among the principal objects which the present invention has in view are: to prevent congestion of freight on a pier of the character mentioned; to facilitate the handling of freight while being received by and delivered from the pier; to facilitate the distribution of freight received on the pier for trans-shipment; and to increase the stowage capacity of the pier.

Drawings.

Figure 1 is a plan view of a pier constructed and arranged in accordance with the present invention, showing in full lines the overhead distributing system, and in dotted lines the subway with which the pier is furnished; and

Figure 2 is a cross section of the pier, the section being taken as on the line 2—2 in Figure 1.

Description.

Piers of the character mentioned are usually constructed in the form of long and relatively narrow buildings, having a number of ports or entrances, along the sides and across the outer or water end thereof, and but one entrance at the land end. As a result of this arrangement, the pier becomes excessively congested at certain times, and the passage between the stored freight on both sides of the pier is encroached upon to such an extent that occasionally room is not left for the passing of vehicles entering and leaving the pier. Further, and under the best conditions, room is not provided so that a vehicle coming up from behind another vehicle can pass the other vehicle with the result that the following vehicle necessarily waits until the first vehicle is charged or discharged of its load. The result of this lack of facility for handling freight on the pier is that the pier becomes rapidly congested, so that freight is removed therefrom or delivered thereon very slowly.

It is the object of the present invention to overcome this difficulty by arranging and equipping the structure of the pier so that

freight may be taken from a vehicle at the land entrance of the pier to be handled mechanically and manually, while distributing it on the pier.

To this end a subterranean tunnel 7 is formed. The tunnel 7 is constructed of very heavy concrete walls 8, which are preferably supported on a system of piles 9. The tunnel 7, as best seen in Figure 1 of the drawings, extends lengthwise of the pier, and preferably at the land side thereof extends beyond the pier so that the receiving end thereof is covered normally by doors 10. A corresponding pair of doors 11 normally closes the delivery opening at the outer or water end of the pier.

A system of tracks is provided in the tunnel 7, the tracks referred to being comprised by the rails 12, on which the wheels 13 of flat cars 14 run. At each end of the tracks the rails are arranged to form a switchback 15. By this arrangement the cars on both sides of the tunnel may be run into the receiving station under the doors 10 or on to the delivery station under the doors 11 at the opposite ends of the tunnel, in one case to receive the load, and in the other case to be relieved therefrom.

The loads deposited on the cars having the platforms 14 are raised by an overhead traveling hoisting mechanism 16. The hoisting mechanism 16 is preferably provided with an independent prime mover, and a winch 17, mounted thereon, upon which winch the cables 18 are wound. The mechanism 16 is suspended from tracks formed at the edge of a girder 19 that extends lengthwise of the pier, and is supported from the strings 20 of the roof trusses of the pier. There preferably are two hoisting mechanisms, that at the forward end being designed to relieve the vehicles of their loads, and to lower the same into the tunnel for disposition upon the flat cars 14 in said tunnel. The hoisting mechanism at the receiving end of the pier may, however, be employed for distributing the loads of the vehicles for stowage on the pier at the land end thereof, without sending the load through the tunnel 7. Say, however, the load is deposited on the cars in the tunnel and carried thereby to the delivery end of the tunnel, the doors 11 being then open to permit the hoisting mechanism at that end of the pier to engage the load, or, if desired, the car itself can

be hoisted from the tunnel and while suspended can be carried lengthwise on the pier to be deposited on the floor thereof in a position suitable for the storage desired. Having deposited its load, the hoisting mechanism, which is carried to the outer end of the pier, returns to receive a second or successive load.

For distributing the freight after the 10 same has been deposited in the center of the pier by the hoisting mechanism, there is provided two laterally extending cranes 21, the cranes 21 being supported on wheels 22, the sides of said cranes providing a track 15 having a movable hoisting mechanism 23. The hoisting mechanism 23, as seen best in Figure 2 of the drawings, employs cables 24, and is provided with a caboose 25, in which an engineer or operator rides. Any suitable 20 means is employed for moving the cranes 21 lengthwise of the building on the tracks 26, which are disposed substantially as shown in Figure 2 of the drawings, the inner tracks being suspended from hanging brackets, 27, 25 while the outer tracks are carried on brackets 28, supported by the funnel structure of the pier.

When a pier is constructed and arranged in accordance with the present invention, 30 and as shown in the accompanying drawings, the congestion referred to is avoided, and the distribution of the freight delivered by teams or from steamers is very much more expeditious than by the old method. 35 The freight may be taken on to the pier by delivering it into the receiving end of the tunnel to be rapidly conveyed away therefrom by the cars in the tunnel to the far end thereof, where the hoisting mechanism 16 expeditiously relieves the car of its load to 40 carry the same lengthwise of the pier to deposit it in the station designed therefor. Immediately the freight is deposited by the hoisting mechanism 16, the said mechanism returns to the delivery end of the tunnel 7, 45 and frees the succeeding cars of their load, each time delivering the load to the point best suited therefor, for stowage convenient for rehandling in trans-shipment. 50 It will be understood that the hoisting mechanism 16 passing as it does overhead, can convey freight above obstacles which a vehicle could not pass. As soon as the 55 freight is deposited by the hoisting mechanism 16, the cranes 21 are set in motion to

the end that the hoisting mechanism 23 mounted thereon will run in to the center of the building adjacent the load which has been deposited to engage the same for piling or packing the freight away from the center 60 and at the outer walls of the pier, as is most desired.

Again it will be realized that the overhead system formed by the cranes 21 and hoisting mechanism 23 permit the handling 65 of freight in the manner difficult, if not impossible, to manual labor, both because of the height of the pile which may be formed by the said cranes, and hoisting mechanisms, and by the fact that they can lift any particular load for deposit over formerly placed articles which might otherwise prove an obstruction.

When it is desired the tunnel 7 may be utilized as storage space by leaving the 75 goods on the cars therein. In this manner it will be understood that the increased capacity of the pier would offset the probable increase in the cost of construction thereof, and particularly of the tunnel feature herein 80 described.

Claims.

1. A structure comprising a building, a tunnel extending longitudinally beneath the 85 building, and having one end extending beyond the building and having its inner and outer ends provided with hatchways, conveyor means for receiving material through the outer hatchway and moving the same 90 longitudinally in said tunnel, and overhead carrier means in the building for extracting material from said conveyor means through the inner hatchway and distributing it in the building.

2. A structure comprising a building, a tunnel extending longitudinally beneath the building and having one end opening through the floor of the building and its other end opening exteriorly of the building, conveyor means for receiving material at the outer end of said tunnel and conveying the same longitudinally of the tunnel, and overhead carrier means in said building for removing material from the tunnel 100 through the opening in the inner end portion thereof and distributing the same in the building.

GEORGE WRIGHT.
